CLAIM

The ornamental design for a smartwatch, as shown and described.

DESCRIPTION

FIG. 1 is a front view of a smartwatch;

FIG. 2 is a rear view of the smartwatch from FIG. 1;

FIG. 3 is a right side view of the smartwatch from FIG. 1;

FIG. 4 is a left side view of the smartwatch from FIG. 1;

FIG. 5 is a front view of the smartwatch from FIG. 1;

FIG. 6 is a rear view of the smartwatch from FIG. 1; and

FIG. 7 is perspective view of the smartwatch from FIG. 1.

FIG. 8 is an exploded perspective view of a smartwatch depicting detached modules.

FIG. 9 is an exploded side view of a smartwatch depicting detached modules.

FIG. 10 is a perspective view of a smartwatch depicting a square-faced environment.

FIG. 11 is an exploded side view of the smartwatch depicting a square-faced environment and detached modules.

FIG. 12 is an alternate exploded side view of the smartwatch depicting a square-faced environment.

FIG. 13 is an enlarged exploded view of a portion of the smartwatch.

FIG. 14 is an enlarged perspective view of a segment of the smartwatch shown separately for completeness of illustration; and,

FIG. 15 is an enlarged perspective view of a different segment of the smartwatch shown separately for completeness of illustration.

The broken lines of the FIGURES depict environment; however, the broken lines form no part of the claimed design.

1 Claim, 15 Drawing Sheets
